UNITED STATES PATENT OFFICE.

NATHANIEL G. SIMONDS, OF CHARLESTOWN, ASSIGNOR OF ONE-SIXTH TO
FREDERIC MCMELLON, OF BOSTON, MASSACHUSETTS.

GRAIN-ELEVATOR.

SPECIFICATION forming part of Letters Patent No. 281,572, dated July 17, 1883.

Application filed May 15, 1882. Renewed April 19, 1883. (No model.)

To all whom it may concern:

Be it known that I, NATHANIEL G. SIMONDS, of Charlestown, in the county of Suffolk and State of Massachusetts, have invented a new and useful Improvement in Grain-Elevators, of which the following is a specification.

My invention relates to an improved means of elevating grain from cars, vessels, or other receptacle into a building at any required height; and the invention consists in the employment of two spirally-flanged shafts arranged within tubes—one of which is horizontal and the other vertical—and connected together so that they may be arranged at a right angle, or any other angle, if desired, and used in connection with a rotary fan, by which I combine the elevating property of the screw with an air-exhaust for creating a vacuum. Provision is also made for shutting off the supply of grain in case the tubes should become packed, and also for preventing the escape of the grain from the tubes.

Referring to the accompanying drawings, Figure 1 is a vertical section through an apparatus constructed according to my invention. Fig. 2 is a plan or top view of the same. Fig. 3 is a side elevation of the fan. Fig. 4 is a section taken on line $x-x$ of Fig. 1. Fig. 5 shows the connection of the vertical and horizontal shafts.

A represents an adjustable vertical tube, which is connected to the fixed horizontal tube A' by means of the hinge a and shaft E, so that it can be adjusted to any desired position for elevating grain, and is provided with a hinged hood, b, which prevents the entrance or escape of air to or from the tubes. Within the tubes A A' are fitted shafts C C', carrying the spiral flanges B B'. At the lower end of the shaft C is fixed a screw-propeller, S, which acts directly to elevate the grain at the commencement. The spiral flange in the vertical tube is of a less pitch than that of the horizontal tube.

Above and between the two portions of the horizontal tubes A A' is arranged a fan-blower, J, similar to that shown in Patent No. 169,662, granted to me November 9, 1875, which is caused to rotate from any suitable motive pow-

er by a belt passing over the pulley K on one end of the shaft k of the fan. The other end of the shaft k also carries a pulley, l, over which the belt H' passes, which communicates motion to the shafts C C' through pulley G, shaft E, and bevel-gearing D c c.

To the lower portion of the vertical tube A is fitted a hopper, F, through which the grain to be elevated may be passed to the lower end of the screw B. This hopper is provided with a valve, f, which is kept closed by means of a spring, g, but which will yield with the weight of the grain in the hopper F when the same is being fed, and will close should the grain become tightly packed in the tubes, and prevent the grain being forced out at the hopper, 65 thus allowing the screw to free itself, which being accomplished the valve f will again open, when the feed is continued. When the machine stops, the grain in the tube A will fall and close the valves f f', which will prevent 70 the grain from passing out of the tube. The end of the tube A is also provided with a short piece of tube, H, fitted with a valve, f', and spring g', like and operating in the same manner as the valve f in the hopper F, before described, the object of this arrangement being that the apparatus can feed itself from a car, vessel, or other place, as desired. Either one or both of these feed-inlets may be employed on the same apparatus. When the grain is fed 80 through tube H the hopper F may be removed and its place supplied by a cap, and a cap is also placed on the lower end of the tube H when the latter is not in use.

In order to prevent the grain going into the 85 gears I provide a slide, n, attached to a thin metal plate connected to the shaft C, so that in changing the angle of the tube A the slide will be moved so as to close the opening. The cylinder inclosing the fan is extended underneath, as shown at m, Fig. 1, and is set very near to the end of the fan, so as to cause the air to pass out underneath the fan with its full force through the tube B". Power being applied to the pulley K by belting from any suitable motor, the fan J is rotated, which causes a vacuum in the tube A'. At the same time the screws B B' are caused to revolve by belt

H', the grain being fed in at the hopper F or by the tube H, it is drawn by the vacuum and carried upward and forward by the screws until it has passed the fan J, when it is still carried forward by the screw B' and the pressure of the air from the fan J to the desired or required place.

In the drawings, Fig. 1, I have shown a space between the shaft B' B'' just below the fan J; but it is evident that the shaft and screw may be continuous.

What I claim as my invention is—

1. The combination of an upright flanged shaft within a tube, A, with a horizontal flanged shaft within a tube, A', the two shafts and tubes being so constructed as to enable the upright shaft to be set at any angle with the horizontal shaft and tube, substantially as set forth.
- 15 2. The combination of an upright and a horizontal flanged shaft arranged within tubes with a fan-blower, as and for the purpose set forth.

3. The screw-propeller S at the lower end of shaft C, in combination with the flange, as set forth.

4. The hopper F, provided with the valve f, in combination with the tube A and flanged shaft B C, as set forth.

5. The extension-pipe H, provided with a valve, f', in combination with the propeller S, tube A, and flanged shaft B C, as and for the purpose set forth.

In testimony whereof I have signed my name to this specification in the presence of two subscribing witnesses.

NATHL. G. SIMONDS.
